(57) **CLAIM**

The ornamental design for a thermal battery assembly as shown and described.

DESCRIPTION

FIG. 1 is a perspective view of a front of an embodiment of a thermal battery assembly in accordance with the present invention.

FIG. 2 is a front elevational view of the thermal battery assembly of FIG. 1.

FIG. 3 is a side elevational view of the thermal battery assembly of FIG. 1.

FIG. 4 is another side elevational view of the thermal battery assembly of FIG. 1, which view is opposite to that of FIG. 3.

FIG. 5 is a back elevational view of the thermal battery assembly of FIG. 1.

FIG. 6 is a bottom view of the thermal battery assembly of FIG. 1.

FIG. 7 is a top view of the thermal battery assembly of FIG. 1.

FIG. 8 is a perspective view of a front of a second embodiment of a thermal battery assembly in accordance with the present invention.

FIG. 9 is a front elevational view of the thermal battery assembly of FIG. 8.

FIG. 10 is a side elevational view of the thermal battery assembly of FIG. 8.

FIG. 11 is another side elevational view of the thermal battery assembly of FIG. 8, which view is opposite to that of FIG. 10.

FIG. 12 is a back elevational view of the thermal battery assembly of FIG. 8.

FIG. 13 is a bottom view of the thermal battery assembly of FIG. 8; and,

FIG. 14 is a top view of the thermal battery assembly of FIG. 8.

The portion of an article depicted in broken lines in the drawings forms no part of the claimed design.
